UNITED STATES PATENT OFFICE.

OTTO HESSER, OF CANNSTATT, GERMANY.

MACHINE FOR MAKING PAPER BAGS.

No. 865,779.

Specification of Letters Patent.

Patented Sept. 10, 1907.

Application filed September 22, 1905. Serial No. 279,746.

To all whom it may concern:

Be it known that I, OTTO HESSER, a citizen of the German Empire, residing at Cannstatt, in the Kingdom of Würtemberg, Germany, have invented certain new and useful Improvements in Machines for Making Paper Bags, of which the following is a description, reference being had to the accompanying drawing, and to the letters and figures of reference marked thereon.

This invention relates to paper bag machines, and 10 has for its principal object to properly feed and assemble outer and lining sheets for the manufacture of lined paper bags.

A further object of the invention is to provide means whereby one of the sheets is supplied with gum or 15 paste at the beginning of the feeding operation, and thereby caused to adhere to the gum-applying member, which latter also serves as a sheet-raising and feeding member.

Further objects of the invention are to prevent the 20 feeding of more than a single sheet at each movement of the feeding devices; to properly grip and convey the sheets, and to properly position the sheets with respect to each other.

With these and other objects in view, the invention 25 consists in the combination of elements described in the accompanying specification, and referred to in the appended claims.

In the accompanying drawings: Figure 1 is an end 30 elevation of a sheet-feeding machine constructed in accordance with the invention, one of the main shafts being shown in section; Fig. 2 is a sectional elevation of that portion of the mechanism employed for lifting the outer sheets; Fig. 3 is a plan view of the parts shown in Figs. 1 and 2; Fig. 4 is a detail sectional view, on an enlarged scale, of the stripper fingers for preventing the feeding of more than a single sheet; Fig. 5 is a plan 35 view of the same. Fig. 6 is a vertical sectional view of the complete feeding machine; Fig. 7 is a transverse sectional view of a portion of the same, showing the stop fingers for the outer shaft; Fig. 8 is a plan view of a portion 40 of the table, showing the location of the stop fingers; Fig. 9 is a vertical sectional view of a portion of the table, showing the stops for preventing rearward movement of the outer sheets; Fig. 10 is a plan view of the 45 same; Fig. 11 is a side elevation of that portion of the machine which includes the mechanism for feeding the inner or lining sheets; Fig. 12 is a vertical sectional view of a portion of the same; Fig. 13 is a plan view of the mechanism shown in Figs. 11 and 12; Fig. 14 is an 50 elevation, on an enlarged scale, showing the location of the strippers which act on the front edges of the lining sheets; Fig. 15 is a plan view of the same; Fig. 16 is a vertical section illustrating the construction

and arrangement of the suction lifter, which acts on the rear edges of the lining sheets; Fig. 17 is a front elevation of the same; Fig. 18 is a side elevation of a portion of the lining sheet feeding devices, showing a modified form of sheet retaining finger; Fig. 19 is a vertical sectional view of the same, on an enlarged scale; Fig. 20 is a vertical section of the lining sheet feeding devices, on an enlarged scale; Figs. 21 and 22 are similar views, illustrating different stages of the operation; Fig. 23 is an elevation, showing the lifting and conveying mechanism for the lining sheets; Fig. 24 is a plan view of the conveying mechanism shown 65 in Fig. 23; Fig. 25 illustrates on an enlarged scale, the construction of the sheet grippers of the conveying mechanism; Fig. 26 is a front elevation of the same; Fig. 27 is a front elevation of the movable stop and clamp for holding both sheets on the table; Fig. 28 is 70 a plan view of a portion of the same; Fig. 29 is a vertical section on an enlarged scale, of the table and the stop and clamp devices; Fig. 30 is a plan view showing the conveyer and guides for the outer or main sheet; Fig. 31 is an elevation of the clamping fingers for holding the edges of the outer sheet immediately after they 75 are raised from the pile; Fig. 32 is a similar view, on an enlarged scale, of one of the clamping fingers; Fig. 33 is a plan view of the complete feeding mechanism; and Fig. 34 shows the assembled sheets in plan, side 80 and edge view.

Similar numerals of reference are employed to indicate corresponding parts throughout the several figures of the drawings.

The main frame comprises two sections, of which the 85 lower section 1 is provided with bearings for the support of the main cam shafts, while the upper section 2 supports the various working parts of the machine.

At one end of the machine is arranged a support for the outer sheets 3, and at one side is a support for the 90 lining sheets 62, and the function of the machine is to raise and deliver one of the outer sheets, supplying the upper surface thereof with an adhesive, and then to place one of the lining sheets on top of such outer sheets, after which the united sheets are moved to the folding 95 mechanism. The pile of sheets 3 is arranged on a suitable support, which receives a short step by step upward movement to compensate for the removal of successive sheets from the pile. The sheets are arranged under a horizontally disposed plate 2^a, which carries an 100 adhesive supply or "gumming" tank 7, into which extends a gumming roller 7^a.

Projecting upwardly from the frame 2 is a vertical 105 guide bar on which a carriage 19 is slidably mounted, said carriage being vertically reciprocated by a cam b on a shaft 34, that is mounted in bearings in the lower

frame 1. The cam actuates a rod 22, that is connected to one arm of a lever 24, fulcrumed on a pin 23 on frame 2, and the opposite arm of the lever is connected by a link 25 to the carriage 19.

5 The carriage 19 is provided with a forwardly extending horizontal arm 17, on which a slidably mounted carriage 6 is supported, and to one face of said carriage is secured a vertically grooved block 6^a, which receives a slide block 16^a, and in the block fits a pin 16, that projects from the lower end of a rocker arm 15, secured to a rock shaft 14.

The shaft 14 is mounted in suitable bearings in the frame 2, and carries at one end a rocker arm 13, that is connected by a helical tension spring 18, to a fixed 15 point on the frame. The rocker arm 13 is connected by a link 12 to one arm of a lever 11, that is fulcrumed on a stud 9, carried by a frame bracket 10, and the opposite arm of said lever is actuated by a cam *c* that is mounted on a transversely disposed shaft 8, supported in bearings in the lower frame 1, and connected to shaft 34 by miter gears. It is clear that rocking movement imparted to the shaft 14 will traverse the pin 16 in the 20 slotted bar 6^a, and effect reciprocatory movement of the carriage 6 on its supporting arm 17.

25 The carriage 6 has a depending arm 5, to which is secured a gum-applying and sheet-lifting stop 4, the latter being traversed over the gumming roller 7^a, and then descending into engagement with and raising the top sheet from the pile 3. The extent of downward movement is limited by a stop rod 26, that is adjustably secured to a bracket projecting from the vertically movable carriage 19.

As successive sheets are removed from the pile, it is necessary to raise the support of the latter and for this 35 purpose the support is provided with a rack 29, engaged by a gear 28 on a shaft 29^a. On this shaft is secured a ratchet wheel 27, that is engaged by a pawl 27^a, operated by a bell crank lever 27^b, and a rod 27^c from the lever 24.

40 The strip 4 presses with some force on the uppermost sheet, and when raised carries the sheet with it. In many cases one or two sheets will cling to the one being raised, and will move upward with it, and to prevent the delivery of more than a single sheet at each operation, a plurality of stripper fingers 30 are employed, 45 these being adjustably secured to the upper portion of the guide box or strips, and serving to engage with the edges of all the sheets raised and prevent the passage of all except the sheet which is clinging to the gumming strip 4.

50 The forward, gummed edge of the sheet is raised slightly above the lower surface of the plate 2^a, and while the sheet is held in this position, its opposite side edges are engaged by clamping fingers 32, that are pivoted on pins 33 at the rear edge of plate 2^a, and are clamped against the lower face of said plate.

55 The clamping fingers 32 are moved to open or release position by cams *c*, *c*, on shafts 34, 35, which transmits motion to the fingers through rods 36 and said rods are engaged by clamp-closing springs 36^a, extending between collars on the rods, and the fixed frame 1, as shown in Fig. 31.

60 At a point in advance of the plate 2^a is a table 38, in the upper surface of which are formed dove-tailed 65 grooves for the reception of two parallel bars 31, the

outer ends of which carry a sheet feeding plate 39 (Fig. 30) that moves under the elevated front edge of the sheet raised by the gumming strip 4, until the feeding fingers 40 at the rear edge of the plate are slightly beyond the rear edge of the sheet, the latter resting thereon in readiness to be transferred to the table 38. The bars 31 also carry a pair of feed fingers 110 (Fig. 30) which, at a second movement, transfer the sheets from the table 38 to other conveying mechanism by which the sheets are fed to the folding devices. 75

The bars 31 have pendent brackets 31^a, which are connected by a link 44 to one arm of a bell crank lever 43 that is pivoted on a stud 42, projecting from frame 2 (Fig. 6). The opposite arm of the bell crank lever is connected to a rod 41, which receives motion from a cam *d* on the shaft 8. In order to stop the movement of the sheet at the proper point on table 38, two stop fingers 45 are employed. These fingers are carried by arms 46, that project from a yoke-like carrying bar 48, the downturned ends of which are pivoted on pins 47, projecting from the opposite sides of the table 38 (Figs. 7 and 8). To one end of bar 48 is secured a rocker arm 50, that is connected to one end of a rod 49, receiving motion from a cam *e* on the shaft 8. During the return of the bars 31 and plate 39 for another sheet, there is some tendency to carry back the previously fed sheet. To prevent this, a pair of stops 109 are arranged to move through openings or recesses in the table 38, and engage the rear edge of the sheet. These stops are carried by arms 127, supported by a cross bar 128. 95 The bar 128 is mounted on pivoted arms 131 (Figs. 6, 9 and 10) and said arms or one of them, is or are operated by a cam *o* on shaft 8, through the medium of a rod 129. As the sheet moves forward on the plate 39, its opposite edges are engaged by fixed guides 51 and 51^a, which 100 guide the sheet laterally to proper position. One edge of the sheet is also clamped to the table 38 by the mechanism shown in Figs. 27, 28 and 29, but as this operates also on the lining sheet, its construction and operation will be described hereinafter. 105

The pile of inner or lining sheets 62 is mounted on a suitable support, which is also provided with means for raising it gradually as the sheets are removed. This support is at one side of the machine, immediately under two pneumatic lifting devices 53 and 72, which 110 are arranged to engage near the opposite edges of the successively uppermost sheets.

The primary or initial lifting member for the lining sheet is in the form of a tube 53, shown in the present instance as of segmental form in cross section, and provided with openings in one of its flat faces. This tube has circular end portions that are mounted in bearing blocks 55, movable vertically in guideways formed at the opposite sides of a frame 52. The bearing blocks also carry a bar 116, that is parallel with the tube, and disposed slightly in advance of the latter. This bar carries spaced bars or plates 115, curved to partly encircle the tube, and provided with a number of stripper plates or fingers 115^a, that are arranged in an arcuate series, and serve, as the tube revolves, to engage and remove all sheets, except the top one, so that if a number of sheets cling together and move upward with the tube, all save the top sheet will be forced down onto the pile. 120

One end of the tube is closed, and is engaged by a 130

coiled spring 117, that tends to keep the tube in the position shown in Fig. 20. The opposite end of said tube is connected by a flexible tube 60 (Fig. 17) to a suction pump 61, that is operated by a cam *g*, on the shaft 34, 5 the cam being properly timed to actuate the pump and exhaust the air from the tube, so that the uppermost sheet will cling to that side of the tube in which the perforations 53 are formed.

In brackets 65 on frame 52 are bearings for the reception 10 of a shaft 57. At one end of the shaft is pivoted a lever 58, the lower end of which is connected by a link 59 to an arm projecting from the end of the tube 53. This lever is connected to the upper end of a rod 56, the lower end of which is actuated by a cam *f*, on the 15 shaft 34, the tube being rocked through an arc of 90°, or between the two positions shown in Figs. 20 and 21.

To the opposite ends of the rock shaft 57 are secured arms 69 and 70, carrying links 71, to which the ends of the tube 52 and the bearings are hung. The arm 20 69 is connected by a rod 68 to a suitable cam on shaft 34, which effects vertical movement of the suction-lifting tube between the positions shown in Figs. 21 and 22.

The operation of this mechanism as thus far described, is as follows: With the tube 52 in the position shown in Fig. 20, the air is exhausted by pump 61, so that the uppermost of the pile of sheets 62 will cling to the perforated side of the tube. The tube is then turned, by operating arm 58, to the position shown in 25 Fig. 21. This operation will usually result in raising the edges of two or more sheets, and as these sheets pass the strippers 115', they are separated from the topmost sheet and fall toward the pile, the movement being rendered certain by one or more retaining fingers 30 63, carried by a rock shaft 64, adapted to bearings in the brackets 65. This shaft carries at one end a rocker arm, which receives motion from a cam *h* on shaft 34, through the medium of a rod 66. The rock shaft 57 is then turned, and the tube 52, and its bearings 55 are 35 raised by links 71, to the position shown in Fig. 22. The opposite or front edge of the sheet is operated upon by suction lifting heads 72, that are carried by a tube 73. Each of these heads has its lower face inclined from the sides toward the center to form a contact 40 surface of reduced area, while the openings in the heads are on that side nearest the edge of the sheet, so that the edge will be turned up slightly, as shown in Fig. 22. The tube 73 is supported by an arm projecting from a vertically slidable carriage 84, that is guided 45 on a vertical arm 85, carried by the frame (Figs. 11 and 12). To the upper end of the carriage is connected a link 83, hung from one arm of a lever 82, that is fulcrumed on a pin 81, carried by the frame. The opposite arm of this lever is connected by a rod 80, to a bell 50 crank lever 79, fulcrumed on a stud 78, and the bell crank lever receives motion from a cam *l* on shaft 8, through the medium of a rod 77. The upper end of the tube 73 is connected by a flexible tube 74 to a suction pump 75, which is actuated by a cam *k* on the shaft 34 55 (Fig. 11). A suitable mechanism may also be employed to effect the step by step upward movement of the support for sheets 62, a portion of this mechanism being shown at 27', 28', and 29', of Figs. 11 and 12. As the suction heads 72 rise, they carry with them the 60 outer edge of the upper sheet, and in many cases one

or two other sheets will also be raised. In order to prevent the delivery of more than a single sheet, the side bars of the paper guide are provided with stripper fingers 76, which engage with the edges of all of the raised sheets and separate those clinging to the topmost sheet. 70 The raising of the front edge of the sheet is accomplished as the rear edge is elevated by the suction lift tube 52, so that the sheet is moved up to the position shown in Fig. 22 in readiness to be conveyed to a position over the outer sheet previously placed on the table 38. 75

At a point to one side of the table 38 is a bracket 91, having a horizontally grooved guide 90, in which is mounted a slidable bar 89, disposed in a horizontal plane slightly above the plane of the table 38, and carrying plate 39. This bar 89 is connected by a link 94 to one arm of a lever 93, that is pivoted on a stud 92. The lower arm of the lever is connected to a rod 133, extending transversely of the frame, and operated by a cam *m* on the shaft 34. 85

At the front end of bar 89 is secured a plate 124, which is projected to a position under the edge of the raised sheet, as shown in Fig. 22. The plate 124 carries standards 87, in which are journaled two shafts 88 and 122 (Figs. 25 and 26). The shaft 88 carries a torsion spring 90 118, and the shaft 122 carries a similar spring 121. One end of each spring is connected to one of the standards 87, and tends to turn the shaft to which it is connected. 90

The shaft 88 carries two gripper fingers 86 and 86", which moves from the full line position of Figs. 25 and 26 to the dotted line position of Fig. 25, to clamp the edge of the raised sheet against the upper surface of the conveyor plate 124. The shaft 88 also carries a shouldered locking disk 119, which is engaged by a locking pawl 123, on shaft 122, the pawl holding the shaft with 100 the grippers in the open position shown in Fig. 25, against the stress of spring 118. The outer end of the pawl is in the path of downward movement of the tube 73, and as the latter descends from the position shown in Figs. 22 and 25, to lay the edge of the raised sheet on 105 the plate 124 the pawl will be tripped, the disk released, and the grippers will move down upon the edge of the sheet of paper. The bar 89 is then moved to carry the sheet over the outer sheet previously placed in position, but in order to prevent the sliding of sheet 110 62 on the gummed upper face of sheet 3, a pair of inclined lifting lugs 95 are employed to hold the sheet slightly elevated. When the conveying device nears the limit of its movement, a pin 126 on the gripper 86, engages a fixed stop 125 on the table 38, and the grippers are turned to release position, the shouldered disk 119 being also turned, and being automatically engaged by the pawl 123 so that the grippers are locked in open position in readiness for the next forward movement. It will be observed on reference to Fig. 22 that 115 120 should a second sheet be raised with the top sheet, it cannot be caught by the grippers, the distance between the retaining finger 63 and the plate 124 being greater than the width of the sheet of paper.

In the manufacture of certain classes of paper bags, 125 it is essential that the outer and lining sheets be arranged as shown in Fig. 34, that is, with the edge of the outer sheet projecting beyond the lining sheet at one side, and the edge of the lining sheet projecting beyond the outer sheet at the opposite side. To effect 130

this, and at the same time to hold the sheets in adjusted position during the return of the carrying plate 39, a clamping mechanism of the type shown in Figs. 6, 27, 28 and 29 is employed.

5 At one side of the table 38 is a vertical standard 97, in which is guided a vertically slideable clamp 96, that is moved down to clamp upon the sheet 3 by means of a spring 105. This clamp is provided with a vertically elongated slot, into which extends a pin 104 carried by 10 one arm of a lever 103, which is held down by a spring 107. The lever is pivoted on a pin 102 carried by the frame, and is connected to the upper arm of a rod 101, the lower end of which is connected to one arm of a bell crank lever 100, fulcrumed on a stud 99, projecting 15 from a bracket on frame 1. The opposite arm of the bell crank lever is actuated from a cam *n* on shaft 8, through the medium of a connecting rod 98.

The clamp 96 is elevated during the movement of one of the outer sheets onto the table 38, and as soon as 20 the sheet stops, the clamp descends and holds it in place, the front face of the clamp then forming a stop for limiting the movement of the lining sheet transversely of the table. The bracket 97 also serves as a guide for a lining sheet clamp 106, having curved fingers at its lower end to guide the sheet downward. This clamp 106 is provided with a horizontally elongated slot which also receives the pin 104, to permit the travel of the pin in its arcuate path. The construction is such that while clamp 96 may descend to 25 hold the outer sheet, clamp 106 may be kept elevated until the lining sheet is fed, and then allowed to move down to clamp said lining sheet, and hold the same during the return movement of the plate 39.

In Figs. 18 and 19 is illustrated a modification of the 35 sheet-retaining finger 63. In this construction, one or more tubes 112 are carried by a hollow shaft 114, one end of which is connected by a flexible tube 132 to the air pump 61, a suitable cock 113 being interposed in the connection. The shaft may be rocked to allow 40 the tubes to act as retaining fingers, and at the same time jets of air may be directed through the tubes to separate accidentally raised sheets from the sheet clinging to the suction lift tube 52.

Briefly described, the operation of the machine is 45 as follows: The uppermost sheet of the pile 3, is engaged by the gumming strip 4, and the sheet adheres to and is elevated by the strip as the latter moves up, while any lower sheets which may cling to the topmost will be engaged and removed by the strippers 30. 50 When the sheet engages the lower face of the plate 2^a, its opposite edges near the gummed surface are caught and held by the fingers 32, while the strip 4 continues its upward movement and leaves the sheet. The plate 39 carried by bars 31 then moves under the sheet 55 and as it returns, carries the sheet over table 38 until the forward edge of the sheet engages the stops 45, the sheet being guided laterally by the strips 51 and 51^a, after which the clamp 96 descends and holds in its place. In the meantime, the outer edge of one of the 60 sheets 62 has been turned up by the suction lift tube 52, any adhering lower sheets being removed by the strippers 115, and then retained by the fingers 63. The tube 52 then carries the sheet upward a short distance, and the inner edge of the sheet is elevated, to a 65 greater distance, by the suction heads 72. The sheet is

raised above the plate 124, and as the tube 73 moves down the edge of the sheet drops on the plate, and the tube engages and trips the pawl 123, and disk 119, whereupon the grippers 86 and 86^a descend and clamp the sheet against the plate. As the plate and grippers 70 move back the sheet is carried over the lugs 95, and held above the gummed sheet 3 previously placed on the table 38. The clamp 96 acts as a stop for limiting movement of the sheet 62, and then clamp 106 descends to hold the sheet in place. The stops 109 then move 75 up to engage the edges of the sheets, after which plate 39 returns for a second sheet. As the plate 39 and bars 31 again move forward, the fingers 110 on bars 31 engage the two sheets and feed them to a suitable conveying mechanism, such for instance as the rollers 111. 80

Having thus described my invention, what I claim as new and desire to secure by Letters Patent, is:—

1. In a paper feeding machine, the combination with means for supporting a pile of sheets of paper, of a gum reservoir, a gum-applying strip, means for moving said strip between the reservoir and the successive uppermost sheets of the pile to successively raise said sheets, and a clamping means for engaging and holding the sheets near the gummed edge before the completion of the upward movement of said strip. 90

2. In a paper feeding machine, the combination with means for supporting a pile of sheets of paper, of a gum reservoir, a gum-applying strip, means for moving the same between the reservoir and the successive uppermost sheets of the pile, a plate against which the sheets engage during their upward movement, clamping fingers for forcing the sheet against the plate in advance of the completion of the upward movement of the strip, and means for operating said clamping fingers. 95

3. In a paper feeding device, the combination with means for supporting a pile of sheets of paper, of a gum reservoir, a gum-applying member, a horizontally movable carriage supporting said member, means for reciprocating said carriage, a vertically movable carriage having an arm by which the horizontally movable carriage is guided, means for moving the vertically movable carriage, and means for engaging and holding the sheets of paper in advance of the completion of the upward movement of the strip. 10

4. In a paper feeder, gum applying member for engaging and raising the successive uppermost sheets of a pile, means for clamping said sheets in advance of the completion of the upward movement of the gum applying member to permit the separation of the latter from the sheet after the latter is fully raised, a conveyer plate movable under 11 the partly raised sheets, and means for operating said conveyer plate. 11

5. In a paper feeding machine, means for supporting a pile of sheets of paper, a table having stops against which the sheets are to be fed, a conveyer plate, bars carrying 12 the plate and slideable in grooves formed in the upper portion of the table, means for actuating said plate and bars, a gum reservoir, a gum-applying and sheet-raising member movable between the reservoir and the successive uppermost sheets of a pile, and means for clamping and holding 12 the raised sheets in position to permit the separation of the gum applying member from the sheets and the passage of a conveyer plate beneath them. 12

6. In a paper feeding machine, a table, means for supporting a pile of outer sheets and a pile of lining sheets, 13 means for applying gum to the outer sheets, and for feeding the sheets successively to a position on the table, means for raising and conveying the successively uppermost lining sheets to a position over the previously placed outer sheets, and independent and successively operable 13 means for holding said sheets in adjusted position on the table. 13

7. In a paper feeding machine, means for supporting a pile of outer sheets and a pile of lining sheets, means for applying gum to the successively uppermost outer sheets, 14 and for raising and conveying the same to position on the

table, a clamping member for holding the sheet in position on the table, means for raising and conveying the successively uppermost lining sheets to a position over the outer sheet and against said clamp, the latter serving as a guide for positioning the lining sheet.

8. In a paper feeding machine, a table, means for gumming and feeding outer sheets to said table, and a second feeding mechanism for conveying lining sheets over the outer sheets in a direction at a right angle to the path of movement of said outer sheets, and inclined blocks over

which the sheets are fed, said blocks serving as lifters to hold the lining sheets elevated until in position with respect to said outer sheets.

In testimony whereof I affix my signature, in presence of two witnesses.

OTTO HESSER.

Witnesses:

WALTER SCHWAEBSCHE,
WILLY HEINRICH.
